(57) **CLAIM**

The ornamental design for a tailgate for a vehicle, as shown and described.

DESCRIPTION

This application contains subject matter related to the following co-pending U.S. design patent applications:

Application Ser. No. 29/813,878, filed Nov. 2, 2021 and entitled “TAILGATE FOR A VEHICLE”; and

Application Ser. No. 29/842,468, filed herewith and entitled “MOTOR VEHICLE, TOY REPLICA, AND/OR OTHER REPLICA”.

FIG. 1 is a front view of a tailgate for a vehicle according to the design;

FIG. 2 is a left, bottom perspective view thereof;

FIG. 3 is a right, front perspective view thereof;

FIG. 4 is a left side view thereof;

FIG. 5 is a right side view thereof;

FIG. 6 is a top view thereof;

FIG. 7 is a bottom view thereof; and,

FIG. 8 is a rear view thereof.
